UNITED STATES PATENT OFFICE.

ED BROWN, OF WASHINGTON, DISTRICT OF COLUMBIA.

PISTON RING.

Application filed August 30, 1926. Serial No. 132,496.

The present invention relates to piston packing or devices commonly known as piston rings, the primary object of the invention being to provide a ring which will automatically seat itself within the ring groove of the piston, and one which will insure a close-fit with the cylinder wall.

An important object of the invention is to provide a sectional ring, the construction of the sections being such that one section will exert an outward pressure on its cooperating section to cause the ring to closely engage its cylinder wall.

A still further object of the invention is to provide a sectional ring so constructed that the sections will be held in close engagement with each other at all times, eliminating any possibility of the sections becoming disengaged to rattle or allow oil to pass by the ring.

With the foregoing and other objects in view which will appear as the description proceeds, the invention resides in the combination and arrangement of parts and in the details of construction hereinafter described and claimed, it being understood that changes in the precise embodiment of the invention here disclosed, may be made within the scope of what is claimed, without departing from the spirit of the invention.

Referring to the drawings:

Figure 1 is a transverse sectional view through a ring, showing the same as positioned on a piston and held within a cylinder.

Figure 2 is an enlarged sectional view through a portion of the ring.

Figure 3 is an enlarged sectional view through a modified form of ring.

Figure 4 is a still further modified form of the invention.

Referring to the drawing in detail, the piston ring embodies an inner section 5 and an outer section 6, the sections having conical surfaces 7 extending from the edges thereof to points substantially intermediate the side edges of the assembled ring, the conical surfaces 7 merging into cylindrical surfaces 8 that finally merge into conical surfaces 9.

As shown by Figure 3 of the drawing, the inner section 10 is provided with a conical surface 11 and a substantially cylindrical surface 12, the upper and lower ends of the substantially cylindrical surface 12 being curved as at 13, the surface 13 at the lower end of the surface 12 merging into a conical surface 14, which surfaces cooperate with correspondingly shaped surfaces formed on the outer section 15.

In the form of the invention as shown by Figure 4, the ring embodies sections wherein the cooperating surfaces thereof are step-like in formation, the ring sections having conical surfaces 16 and 17, the conical surface 16 terminating in a substantially cylindrical surface 18, spaced from the inner edge of the inner ring section.

A cylindrical surface 19 connects the conical surfaces of the inner section while a cylinder surface 20 connects the conical surfaces of the outer section of the ring.

From the foregoing it will be seen that due to the construction shown and described, the conical surfaces contacting with each other, will cause the sections to move with respect to each other insuring a close-fit between the ring and walls of the ring groove in which it is positioned, and will also cause the outer ring section to expand to closely engage the cylinder wall in which the piston is moving.

I claim:

1. A piston ring including an inner section and an outer section, said inner section having upper and lower outer conical surfaces and having a substantially cylindrical surface connecting the conical surfaces, said outer section having upper and lower inner conical surfaces connected by a substantially cylindrical surface, the conical surfaces cooperating to spread the ring vertically, and said cylindrical surfaces being spaced apart to allow movement of one section with respect to the other section.

2. A piston ring including an inner section and an outer section, said inner section having upper and lower outer conical surfaces and having a substantially cylindrical surface connecting the conical surfaces, one

of the conical surfaces intersecting the end surface of the section, said outer section having upper and lower inner conical surfaces connected by a substantially cylindrical surface, the conical surfaces cooperating to spread the ring vertically, and said cylindrical surfaces being spaced apart to allow movement of one section with respect to the other section. In testimony that I claim the foregoing ¹⁰ as my own, I have hereto fixed my signature.

ED BROWN.
